UNITED STATES PATENT OFFICE.

CATHARINE L. GIBBON AND THOMAS H. GIBBON, OF NEW YORK, N. Y.

COMPOUND RAIL FOR RAILWAY-TRACKS.

SPECIFICATION forming part of Letters Patent No. 459,781, dated September 22, 1891.

Application filed June 27, 1890. Renewed August 24, 1891. Serial No. 403,509. (No model.)

To all whom it may concern:

Be it known that we, CATHARINE L. GIBBON and THOMAS H. GIBBON, both of the city, county, and State of New York, have invented 5 new and useful Improvements in Rails for Railway-Tracks, of which the following is a specification.

Our invention relates to improvements in compound rails for railway-tracks; and it 10 consists in forming said rails in two sections, which are joined longitudinally in such manner that the two parts will be mutually interlocked and the head of the rail supported by a flange on the upper edge of the conjoining 15 rail.

In the accompanying drawings, which are herein referred to and form part of this specification, Figure 1 is a transverse section of one form of our compound rail, the end of 20 a conjoining rail being shown in elevation. Fig. 2 is a side elevation of the same, and Fig. 3 is a transverse section and end elevation of a modified form of our compound rail.

As represented in the drawings, our compound rail, whose cross-sectional form closely approximates that of the ordinary T-rail, is composed of a principal rail A and a complementary rail B, which are joined together longitudinally with the conjoining ends of 25 the principal rails placed intermediately between the conjoining ends of the complementary rails, and thereby a series of break-joints is formed throughout the entire length of a track, so as to afford great stability to 30 the track.

The principal rail A embraces a head 1, on which the car-wheels of a train of cars bear, a web portion 2, and a bottom-flange portion 3, as shown in Fig. 1. The head 1 is beveled 35 upwardly and inwardly, as at 4, to form an interlocking member at the upper part of said rail, as shown in Fig. 1. The head 1 is provided with a longitudinal groove 5 on its under side next to the web portion 2, said groove 40 forming one part of an interlocking device at the upper part of the rail, as shown in Fig. 3. The principal rail A is provided with a longitudinal tongue 6, which is formed on the lower part of the inner face of said rail and is fitted 45 to engage with a corresponding groove in the conjoining face of the complementary rail,

and thereby an interlocking device is formed at the lower part of the rail.

The complementary rail B embraces a head flange 7, which, as shown in Fig. 1, is beveled 55 on its upper face to form a close joint with the bevel in the under side of the head of the principal rail, and, as shown in Fig. 3, the said head flange is provided with a longitudinal tongue 8, which is fitted to engage in the 60 longitudinal groove 5 of the principal rail A, and when made in either form shown and described said head flange will interlock with the head 1 of the principal rail A. At the lower part of the inner face of the complementary rail a longitudinal groove or rabbet 65 9 is formed to receive the tongue 6 of the principal rail, and said tongue and groove form an interlocking device at the lower part of the compound rail when the two rails are 70 fitted together, as shown in the drawings. A bottom-flange portion 10 is formed on the lower outer face of the complementary rail, and when the two rails are fitted together, as 75 shown in the drawings, whereby the principal rail A is firmly held, so as to prevent any springing up of its ends from any cause, the bottom-flange portions 3 and 10 will form an ample base for supporting the compound rail.

The principal rail A and complementary 80 rail B are fitted together so that the inner faces of the web portions 2 and 11 will be in contact, and in order to effect this the outer lower edge of the head 1, and the outer upper edge of the head flange 7 must be placed in 85 contact, the complementary rail being held in a fixed position, with the lower part of the principal rail swung away from the complementary rail and the end of the latter about midway of the length of the principal rail. 90 Then by swinging the lower part of the principal rail toward the complementary rail the two will be locked together at top and bottom, so as to prevent any vertical movement of either, and likewise to prevent any direct 95 lateral separation of said rails.

What we claim as our invention, and desire to secure by Letters Patent, is—

A track-rail composed of a principal rail and a complementary rail, said principal rail 100 being composed of a head portion, a web portion, a bottom-flange portion, and a longi-

tudinal tongue at the lower part of its inner face, and the complementary rail having a head flange, a web portion, a bottom-flange portion, and a longitudinal groove at the lower part of its inner face, the head of said principal rail being fitted to overlap and interlock with the head flange of said complementary rail, and the lower tongue of the latter

being fitted to interlock with the corresponding groove of the complementary rail, as and for the purpose herein specified.

CATHARINE L. GIBBON.
